UNITED STATES PATENT OFFICE

LEON CRAIN BISHOP, OF BINGHAMTON, AND SEWARD EUGENE SWICK, OF ENDICOTT, NEW YORK, ASSIGNEES TO INTERNATIONAL TIME RECORDING COMPANY OF NEW YORK, OF ENDICOTT, NEW YORK, A CORPORATION OF NEW YORK

CARD RACK

Application filed September 5, 1931. Serial No. 561,368.

This invention relates to card racks and more particularly to the type of racks used for holding workman's time cards for making up payrolls.

5 In many large manufacturing plants where a weekly payroll is made up it is undesirable to wait until the end of the week before being apprised of the information on the payroll time clock. Accordingly a clerk is sent 10 around to inspect the cards at all of the time recorder stations each day and this clerk takes the cards out of each rack one at a time and inspects them to note any irregularities appearing on the card, making a record of 15 the same in a suitable time book if any such irregularities occur, and then replacing the cards in their respective pockets. This is a time consuming operation and it is the purpose of this invention to provide a card rack 20 to facilitate the removal of these cards so as to reduce the time required for this checking operation to a minimum.

It is also customary in many manufacturing organizations to lock the card racks so 25 that the cards are inaccessible during the night and also to lock the racks after certain hours of the day so that persons who are extremely late in arriving or leave unusually early during normal working periods, cannot 30 immediately gain access to their time cards but will have to apply to the foreman to unlock the rack if they are to have a complete record shown on their card. This gives the foreman an opportunity to check up on the 35 cause of continuous occurrences of this nature. To do this has always required the locking of every rack section individually. In the applicants' arrangement the racks are 40 swung face to the wall which renders the cards therein inaccessible and the locking of one rack only causes all other racks to become interlocked so that they cannot be swung into accessible position.

45 An object of this invention is to provide a card rack constructed in such a way that all of the cards may be removed from the rack in one operation.

Another object of the invention is to provide 50 a card rack having a channel or passage

intermediate the supports for cards to facilitate removal of cards placed therein.

Still another object is to provide a card rack having adjustable abutting supports whereby the card rack may be adapted to receive different length cards. 55

A still further object of the invention is to provide a supporting frame for mounting a series of racks in such a way that when one rack is locked all racks adjacent thereto on 60 said frame also become locked.

A more specific object is to provide a novel card rack constructed wholly of sheet metal stampings and assembled into an integral compact structure without the use of screws, 65 bolts or other separable fastenings as far as possible.

Another object is to provide means for increasing the number of rack units as time goes on and the number of workmen using 70 a particular time clock is increased and to do this in a simple way without structural changes in or alteration of the existing racks.

Other objects, advantages, or features of the invention will be more particularly pointed out in the following specification and claims or will be apparent after a study thereof and of the accompanying drawings which show an illustrative form of embodiment of the invention. 75

In the drawings:

Fig. 1 is a front elevation of the assembled card rack, one of the rack units being shown facing forwardly and another facing rearwardly. 85

Fig. 2 is a top plan view of the assembled rack.

Fig. 3 is an enlarged front elevation of the upper end of one of the rack units.

Fig. 4 is a vertical section on the line 4—4 90 of Fig. 3.

Fig. 5 is a vertical section on the line 5—5 of Fig. 3.

Fig. 6 is a horizontal section on the line 6—6 in Fig. 3. 95

Fig. 7 is a horizontal section on the line 7—7 in Fig. 3.

Fig. 8 is a perspective view of the card stop.

Fig. 9 is a front elevation of the upper part 100

of the assembled card rack showing all of the rack units in locked position.

The card rack comprises a plurality of individual rack elements or units 10 pivotally mounted in a framework, each rack unit being adapted to hold a series of individual workman's time cards. Only three such rack units are illustrated in the drawings but it will be clear that any number might be provided according to the number of workmen who must use the rack. Indeed, it is a feature of the present invention that it is possible to increase the capacity of the rack as a whole by adding new rack units as the need becomes apparent without completely disassembling the rack, only slight changes being required to secure increased card capacity.

Each rack unit, Figs. 3 to 7, is constructed of sheet metal as an integral unit comprising a back plate 11, two front members 12 and 13 mounted in spaced relation upon the back plate 11, a top plate 14 and a bottom plate 15. The members 12, 13 extend vertically and lengthwise of the back plate 11 and are substantially U-shaped in horizontal cross-section as shown in Figs. 6 and 7. Each member 12, 13 is provided with flanges 16, 17, which are secured to the back plate 11, the flanges 16 being secured to the rear face of the back plate while the flanges 17 are secured to the front face of the back plate. Any suitable means may be employed in securing the flanges 16, 17 to the back plate, however, for reasons of cheapness of manufacture spot welding is preferred. The top plate 14 is provided with a flange 18 extending downwardly and secured to the rear edge of the back plate 11 as by welding and is provided with a much longer flange 19 projecting downwardly in front of the upper ends of the members 12, 13 and secured to the latter by spot welding. Both members 12, 13 have a tongue or tab 20 which is bent over the flange 19 and assists in holding together said flange and members 12, 13.

Each of the members 12, 13 is stamped from a single piece of sheet metal and subsequently folded to the cross-sectional shapes shown in Fig. 6 and in their assembled relation provide an open channel or passage 21 extending longitudinally of the rack. This channel or passage constitutes one of the novel features of the invention and is provided for the purpose of permitting a clerk with one sweep of his hand to remove all the cards at once.

When the members 12, 13 are stamped from sheet metal, a series of V-shaped slots 60 are stamped therein and disposed in herringbone fashion on the sheet metal plates comprising said members so that when the members 12, 13 are subsequently folded and assembled on the back plate 11 there will be 65 provided in the assembled rack two rows of

parallel inclined slots 22 and parallel aligned horizontal slots 23. Each slot 22 in member 12 has a cooperating parallel slot 22 in member 13, both being inclined vertically and likewise each slot 23 in member 12 coacts with a similar slot 23 in member 13, the co-acting slots 23 being in alignment axially. The material of the members 12, 13 adjacent the lower edges of the slots 23 is formed as a lip 24 for the purpose of guiding the time cards into their appropriate positions in the slots 22, 23.

Each time card is slipped into a pair of slots 23 and is guided by the lips 24 down into the corresponding pair of slots 22 which support the cards and permit insertion or removal of any individual card without disturbing the others. The cards are guided downwardly and prevented from slipping sidewise in the slots 22, 23 by the outside walls of members 12, 13. A suitable number plate 25 above each pair of slots 23 identifies the workman's card belonging in that slot, the right hand member 13 being somewhat wider than the member 12 in order to 90 allow room for the number plates 25.

When a clerk wishes to remove the cards for the purpose of inspecting them for irregular time registrations or to replace the cards, he merely has to insert his fingers in the channel 21 beneath the edge of the lowermost card and then raise his hand with a quick sweeping movement so as to carry up all cards in the slots, meanwhile permitting the cards to slip into the palm of his hand. As a consequence of this operation all the cards will be removed together and in one packet with the highest numbered card in front. As the part of the card receiving the time imprints usually faces rearwards when placed in either the time clock or the card rack, the packet of cards may be turned over and the time records of the workman inspected in numerical order.

One of the features of the invention is the provision of means whereby various sizes of cards may be accommodated in the rack units. Time cards vary as to length which depends on the duration of the period during which the card is to be used, that is some cards are large enough to receive time entries for a period of two weeks, others only time entries for one week. A firm making up its payroll weekly may decide to make it up every two weeks or every month. The card racks hitherto constructed had no provisions for adapting them for longer or shorter cards and when it was desired to use cards of a different length it was formerly necessary to replace all the card racks, an expensive feature of a change in the payroll period. The present card rack units are so arranged that any length of card may be accommodated and a change in length of the card calls merely for a slight adjustment in

the rack. For this purpose there is provided a card abutment bar 26 for each member 12, 13 which bar is removably secured on the outside of the walls of said members forming 5 the channel 21.

The bar 26 is formed in one piece with a bent over T-shaped lug 27 for each slot 22 adapted to act as a card stop. Each lug 27 projects into the corresponding slot 22 which 10 embraces the narrowed part of said lug so that a card inserted in said slot will drop down until the lower edge of the card rests on the lug 27. The lugs are so disposed on the bar 26 that they will be in vertical alignment when bent-over lugs 28 formed in the 15 ends of the bars 26 are sprung into suitably located holes 29 in the walls of the channel 21 so as to hold the bar 26 in a vertical position. A number of such holes 29 are provided 20 and are so disposed that the bar 26 may be positioned to accommodate various lengths of card by simply springing the lugs 28 from the holes 29, and sliding the bars 26 in a direction to carry the lugs 27 longitudinally 25 of the slots 22 until the lugs 28 in said bars slip into the holes appropriate to the size of card to be used.

Provision has been made for readily changing the rack units to adapt them to receive 20 cards for either in-coming or out-going workmen. The flange 19 of each rack unit has cut therein a rectangular opening 30 behind which is a slide 31 bearing the words 25 "IN" and "OUT" in large type. The slides 31 are guided by virtue of the fact that a portion of the material of the members 12, 13 is cut out at 32 before folding said members so that the slides 31 move in notches in the 30 edges of the walls forming the channel 21 and are guided by the edges of the cut out portion 32 in the members 12, 13. The drawings show the word "IN" as being visible through the opening 30, that is, the rack is 35 arranged to receive the cards of in-coming workmen. Should it be desired to use the rack for receiving the cards of out-going workmen it is merely necessary to slip a finger behind the flange 19 and within the channel 21 and then shift the slide until the 40 word "OUT" is visible through opening 30.

When the number of workmen using a particular time clock is not large and less than the capacity of an individual rack unit 45 10, said unit may be mounted upon the wall or other support upon which the time clock is mounted. For this purpose there is provided irregular holes 33 in the back plates 11.

Under ordinary circumstances it may be necessary to provide several such rack units 50 in order to accommodate a larger number of cards than one rack unit can receive. When more than one rack unit is used, it is advantageous to pivotally mount the rack units in a suitable frame or other support which will 55 permit turning said units face to the wall and

locking them in that position during certain time intervals, usually normal working hours, so that workmen arriving late or leaving early will be obliged to go to the foreman and have him unlock the rack before registering the time of arrival or departure on their time cards. Accordingly, each rack unit has associated therewith a pair of brackets 34 70 each having staked thereto a pivot 35 which pivots are journalled in suitable holes in the top plate 14 and bottom plate 15 so that rack units may be turned face to the wall. 75

In order to lock the rack units in position the right hand unit 10 is provided with a flange 36 (Figs. 1 and 2) which has two holes 80 37 diametrically opposite to the upper pivot 35 of said unit. Cooperating with the holes in the flange 36 is the bolt of a lock 38 by means of which the right hand rack unit 10 may be locked either face out or face to the 85 supporting wall. The two left hand rack units 10 in Fig. 1 are adapted to be raised slightly on their pivots 35 and are provided with holes 39 which register with studs 40 when the units are turned face to the wall in 90 which position said studs 40 project into the holes 39 and prevent said racks from being turned face forward unless the rack units are first lifted to remove the studs 40 from registration with the holes and thereafter turned. 95

In order to lock the two left hand units 10, therefore, it is merely necessary to prevent 100 said units from being raised and this is accomplished by means of plates 41 secured to the tops of all the units. The plates 41 are so disposed on the rack units 10 that when all 105 of the units have been turned face to the wall as in Fig. 9 and the right hand unit locked by means of the key 42, said plates overlap the tops of the adjacent rack units and prevent raising said units to remove the pins 40 from register with the holes 39.

It will be seen that only one lock and key 110 controls the locking of all three rack units and it will be obvious that regardless of the number of rack units in the assembled rack all may be locked securely by merely turning them face to the wall and locking the right hand unit in the manner described.

It will be clear, of course, that the construction just described is only illustrative as by a slight re-arrangement of the parts the left hand rack unit 10 may be used to lock the two right hand units and others in a similar fashion. 115

It is desirable that means be provided for increasing the capacity of the assembled rack as time goes on in order to take care of increases in the number of workmen using the time recorder with which said rack is associated. For this purpose the brackets 34 are so constructed that additional rack units may be added to the left of the existing rack units 125 illustrated in Fig. 1. As shown in Figs. 1 and 2, the brackets 34 are in over-lapping 130

relation and are fastened in place by means of screws 43 which pass through two adjacent over-lapping brackets 34 and secure both of them firmly to the supporting wall. Studs 44 staked in each upper bracket extend into suitable holes in the next adjacent bracket to the right so as to hold said brackets in proper spaced relation.

The left hand pair of brackets 34 is joined by means of an angle member 45 which, together with the brackets 34, forms a suitable frame for the rack units, said angle member 45 having a slot cut therein to receive the plate 41 on left hand rack unit 10 when said unit is turned face to the wall, the slot being large enough to permit the left hand unit to be raised when it is desired to turn the face outward.

When it is desired to add more units to the assembled rack, it is merely necessary to remove the angular member 45 and slip a pair of additional brackets 34 under the already existing left hand bracket shown and screw said brackets in place as shown in said drawings, after first slipping said brackets over the pivots 35 of the new rack unit. The angular member 45 may then be attached to the new pair of brackets 34. By this simple procedure as many rack units as desired may be added to the existing units and these additional units may be locked in the same fashion as the other rack units by turning them face to the wall and allowing the pins 40 of said rack units to register with the holes 39.

This invention has been illustrated and described by means of a specific form of embodiment, however, it is not limited to the specific form shown as modifications or variations may be introduced as occasion demands, all such modifications or variations being within the scope of the following claims:

1. A card rack unit, comprising an integral sheet metal structure including a base member, a pair of hollow box-like members integrally secured to said base member in spaced relation so as to form a channel, the walls of said members forming the channel being provided with parallel inclined straight slots adapted to freely removably support the cards in overlapping relation, said channel being arranged to permit manual removal of all cards at one operation by a vertical sweeping movement of the fingers of the operator inserted in said channel.

2. In a card rack unit, a pair of parallel walls in spaced relation and having slots adapted to receive and support cards, and an adjustable abutment bar carried by one of said walls and having lugs extending into said slots upon which lugs the cards rest.

3. In combination, a plurality of rack units, a support for said units, said rack units being pivotally mounted in said support and adapted to be turned face thereto so as to pre-

vent access to the cards, and means whereby the locking of one of said units face to the support locks the others face to the support.

4. In combination, a plurality of pivotally mounted rack units arranged to be turned face rearwards and locked by a combined longitudinal and rotary movement relative to the axis of the pivots therefor whereby to prevent access to the cards, said rack units having an interlocking relation with each other when turned face rearward, and means for locking one of said units face rearwards thereby locking all of the remaining units by virtue of the interlocking relation of said unit with the remaining units.

5. In combination, a series of rack units each having an interlocking relation with the adjacent rack units, said rack units being adapted to be turned face rearwards in predetermined order, and means for locking the lowest rack unit of the series face rearwards whereby to lock the remaining rack units in said position by virtue of the interlocking relation between adjacent units.

6. In a card rack, a series of rack units each adapted to support a group of cards, a pair of supporting brackets for each rack unit adapted to pivotally support said unit to permit the latter to be turned face rearward, each pair of brackets having a locking pin cooperating with a hole in the associated rack unit to hold said unit face rearward, said unit being disengageable from said pin by a combined lifting and pivotal movement of the unit, means for locking one of said units face rearward, and means carried by each rack unit and having an over-lapping relation with the next adjacent unit for preventing movement of the adjacent unit to disengage the latter from its locking pin whereby the locking face forward of the unit having the locking means effects locking of the other units in said position.

7. A card rack unit, comprising a support, and a pair of card supporting members mounted in spaced relation on said support, said members being hollow boxlike structures in transverse section and secured by parallel flanges to the support and having parallel opposing walls provided with inclined straight slots, for freely removably supporting the cards, in overlapping relation, said opposing walls together forming a channel permitting removal of all of the cards at a single operation.

8. A card rack unit, comprising a support, a pair of card supporting members mounted in spaced relation in said support, each member having inclined parallel slots coacting with similar slots in the other for supporting the cards, and a member adjustably mounted in one of said card supporting members adjacent said slots for adapting the rack to support different sizes of cards.

9. A card rack unit comprising a support,

- a pair of card supporting members mounted in said support and having inclined slots for supporting the cards, and means carried by one of said members for adapting the rack to support different sizes of cards comprising a bar adjustably mounted adjacent the slots and having off-set lugs projecting through the slots upon which lugs the cards rest.
10. In a rack for cards, a support, a plurality of rack units pivotally mounted in said support and adapted to be turned face forward, means for holding said units face rearward and disengageable by a lifting and pivotal movement of the rack units, the latter having an over-lapping relation when in said position, requiring one of said units to be turned face forward before the adjacent units can be disengaged from the holding means, and means for locking the last named unit face rearward thereby preventing the other units from being turned face forward.
11. In a rack for cards, a series of rack units, each adapted to be turned face forward, means individual to each unit for holding said units face rearward, said rack units having an over-lapping relation requiring the units to be turned face forward in a predetermined order to effect release of the holding means, and means for locking one of said units face rearward whereby to prevent said units from being turned face forward in the predetermined order.
12. A rack for cards comprising a support, a plurality of rack units mounted in said support and adapted to be positioned to face rearwardly or forwardly, means for holding one of said units face rearward, means carried by another of said units for preventing disengagement of the holding means when said units are held face rearward, and means for locking the last named unit face rearward thereby to prevent positioning said units forwardly.
13. A card rack unit having a pair of spaced parallel walls, one of said walls being slotted to support and guide the cards, and adjustable means carried by one of said walls and coacting with said slots for adapting the unit to support different sizes of cards in said slots.
14. A card rack unit having parallel walls in spaced relation and provided with slots adapted to support the cards, and means carried by one of said walls for adjusting the rack unit to accommodate different sizes of cards.
15. A card rack unit comprising a pair of spaced parallel members adapted to support cards, and a member adjustably mounted on one of said spaced members for accommodating said spaced members to different lengths of cards, said adjustably mounted member having a plurality of spaced abutments upon which the cards rest.
16. A card rack unit comprising at least one pocket adapted to receive a card and adjustable means co-operating therewith for varying the size of a pocket whereby to accommodate the latter to receive varying sizes of cards.
- In testimony whereof we hereto affix our signatures.
